PERMANENT WAVING APPARATUS

Milton Burton, New York, N. Y., assignor, by
mesne assignments, to Eugene, Ltd., New York,
N. Y., a corporation of New York

Application October 10, 1933, Serial No. 692,962

3 Claims. (Cl. 219—24)

The present invention relates to permanent waving, and more particularly to novel and useful improvements in the electrolytic process of permanent waving.

5 Objects and advantages of the invention will be set forth in part hereinafter and in part will be obvious herefrom, or may be learned by practice with the invention, the same being realized and attained by means of the instrumentalities 10 and combinations pointed out in the appended claims.

The invention consists in the novel parts, construction, arrangements, combinations and improvements herein shown and described.

15 The accompanying drawing, referred to herein and constituting a part hereof, illustrates one embodiment of the invention, and together with the description, serve to explain the principles of the invention.

20 Of the drawing:

Fig. 1 is a perspective view of an electrolytic heating pad in accordance with the present invention;

Fig. 2 is a section taken on the line 2—2 of Fig. 25 1; and

Fig. 3 is a diagrammatic side elevation, partly in section, showing the illustrative embodiment of the invention in use.

This invention has for its object the provision 30 of a novel and improved permanent waving heater particularly adapted for use with white, gray and other light hair, although equally well adapted for general use. Another object is the provision of such a heater having at least one electrode 35 of a polarizable metal which may be of low specific gravity.

Preferably and as embodied, the heating pads comprise an inner perforate electrode of a polarizable metal such as aluminum, an outer 40 electrode of non-polarizable metal, such as lead, and a layer of absorbent electrolyte carrier positioned between and in electrical contact with said electrodes. This carrier is moistened with a lotion comprising an aqueous solution of a volatile alkali, such as ammonia, and a negative ion 45 which attacks the inner electrode to render it non-polarizing, also forming a somewhat insoluble compound with any of the metal of the outer electrode which may be dissolved by the lotion 50 during heating, this insoluble compound being preferably white or of a very light color.

It will be understood that the foregoing general description and the following detailed description as well are exemplary and explanatory of the 55 invention but are not restrictive thereof.

In certain respects the present invention is an improvement on the invention disclosed in the patent to Durham and Finnegan No. 1,926,987 of September 12, 1933, but it is not limited 60 thereto.

Referring now in detail to the present embodiment of the invention as shown in the drawing, the electrolytic heating pad comprises:

An inner electrode 2, to be separated from a wound tress of hair by means of a layer of parchment paper 4 waxed to the inner side of said electrode and perforated in register therewith, as at 6.

A layer of absorbent material 8 adapted to be positioned between the inner and outer foil electrodes and in contact therewith and to be moistened with hair waving, electrolytically conducting lotion.

An outer electrode 10 to contact with the outer face of the carrier 8 and to be wrapped about 15 the wound tress of hair to form a tight envelope surrounding the tress.

The inner electrode 2 is formed from a metal which forms a light-colored or white sulfide and is generally a polarizable metal. For this purpose 20 aluminum or zinc may be used.

The outer electrode 10 is formed from a soft metal which is non-polarizable and such metals generally form colored sulfides and are generally of the fourth group. Suitable metals are lead, 25 tin and various alloys thereof.

The absorbent material 8 may be felt, flannel or absorbent material, and the parts may be secured together in proper relation by a line of stitching 12.

The lotion preferably comprises an aqueous solution of a weak volatile alkali, such as ammonia, suitable negative ions for preventing too rapid volatilization of the ammonia, such as carbonate or borate ions, and negative ions to attack the polarization and destroy its polarization such as chloride, or other halogen ions.

The depolarizing ion employed is also preferably such as to form a light colored, relatively insoluble compound with any of the metal eroded 40 from the outer electrode during the process and thereby reduce the formation of dark colored sulfides which might discolor the hair.

As an example of a suitable lotion for use with an aluminum inner electrode and a lead or tin 45 outer electrode, the following may be given:—

Water	g	388
Ammonium hydroxide 26° Bé	cc	23
Ammonium carbonate	g	37
Sodium or ammonium chloride	do	20
Boric acid	do	45

To this may be added, suitable hair enriching compounds, oils, etc. as desired.

In use, the heating pad, moistened with a small 55 quantity of the lotion is wrapped about a tress of hair 14 wound on a conventional curling rod 16, and wrapped with porous tape 18, so as to form concentric layers; the paper 4 against the tape 18, then the inner foil 2, the electrolyte 60

carrier 8 and finally the outer foil electrode 10.

The inner and outer electrodes are then connected to a source 28 of relatively low voltage alternating current, such as 4 volts, and current is conducted from one electrode to the other through the lotion. The resistance of the lotion to the electrolytic conduction of current causes the lotion to be heated rapidly to boiling, causing liberation of moist ammonia vapor which passes through perforations 8 and is condensed on the wound tress of hair to be permanently waved. This heating action continues for a sufficient time, five to fifteen minutes, depending on the nature of the hair being treated.

15 As the heating continues, lead is dissolved by the electrolytic action of the lotion thereon and this lead immediately reacts with the chloride in the lotion. The chloride also prevents polarization of the aluminum which would otherwise reduce the current flow.

20 The halide in the lotion tends to attack certain metal curling rods, and to prevent this attack, the curling rods may be covered, where exposed by a small piece of paper 13 formed as a part 25 of the pad and secured in position by stitching 12, or the rods as a whole may be lacquered with a non-sticky, lacquer which is not attacked by the lotion such as a phenolic condensation product lacquer.

30 The invention in its broader aspects is not

limited to the specific mechanisms shown and described but departures may be made therefrom within the scope of the accompanying claims without departing from the principles of the invention and without sacrificing its chief advantages.

What I claim is:—

1. An electrolytic heater for use in permanent waving of human hair including in combination a pair of electrodes, one of which is formed from 10 aluminum, and an electrolyte absorbent positioned between said electrodes, said absorbent being moistened with a solution containing hair waving positive ions and halide ions capable of attacking the aluminum. 15

2. An electrolytic heater for use in permanent waving of human hair including in combination a pair of electrodes, one of which is formed from aluminum, and an electrolyte absorbent positioned between said electrodes, said absorbent 20 being moistened with a solution containing a volatile alkaline base and negative halogen ions.

3. An electrolytic heater for use in permanent waving of human hair including in combination a pair of electrodes, one of which is formed from 25 aluminum, and an electrolyte absorbent positioned between said electrodes, said absorbent being moistened with a solution containing ammonium and chloride ions.

MILTON BURTON. 30
